1

The usual presses for earth-pots which are employed for the setting out of plants in nursery grounds and the like, are cumbersome in operation and therefore have a small capacity, even if operated by two persons, since it is necessary at first to fill the mould, then to apply a covering plate over it, then to move the die down and up, then to remove the covering plate and at last to push the pot out of the mould, separate manipulations being necessary for each operation.

It is true that automatically operated presses of great capacity are known for this purpose, but these are rather costly and often have a great number of movable parts, so that they become rather easily damaged. This is particularly undesirable since, as a rule, such presses are operated by laymen.

Earth-pot presses subject to these disadvantages are already known, and they ordinarily comprise a plurality of moulds which are moved intermittently past a pressing position with a pressing die acting from above and an expelling position angularly displaced therefrom. These functions in such a manner that, in each position of rest of the moulds, a pot can be pressed in one mould and a pot can be expelled from a second mould, while a third mould is being filled with earth. Thus mould presses are known in which the moulds are interconnected so as to form a chain, and wherein the pressing takes place while the mould rests on a stationary support, and the expulsion is effected by a common expelling rod, which is pushed horizontally into the mould through an opening in the bottom thereof after the mould has left the support. In these known constructions the necessity of providing a link chain constitutes a complication, and a great number of moulds is required for a given capacity, because the positions on the way back are not utilized.

It is the principal object of the present invention to provide an earth-pot press which apart from having a great capacity which is also cheap to manufacture and is of a simple and, above all, of a robust construction.

The press according to the invention comprises a mould wheel shaped with a plurality of moulds, which by a step by step movement of the mould wheel about a vertical axis is moved past a pressing position with a pressing die acting from above and an expelling position angularly displaced therefrom. The main feature of the press consists in the feature that the pressing die is carried by a rod which passes centrally through the mould wheel and there is provided a fixed

2

bottom plate on which the moulds rest with open bottom, and which is provided with an opening at the expelling position. A very simple and robust construction is thereby attained, as the fixed bottom plate, apart from forming part of the fixed frame of the apparatus, closes the bottoms of the open moulds during filling and pressing and also forms a support and bearing for the mould wheel and the die rod, and even with manual operation a great capacity may be obtained. This is because the arrangement of the die-carrying rod in the center renders the periphery of the mould wheel easily accessible for rotating the mould wheel, filling with earth, removal of finished pots, etc., and thus permits, at the same time, the driving of the die from a pedal in a simple manner.

Further features of the invention will appear from the following description of two constructional embodiments, read in connection with the drawings.

Fig. 1 is a top view of the press according to one embodiment.

Figs. 2 and 3 show the same embodiment in axial sections taken along the lines II—II and III—III respectively in Fig. 1, and

Fig. 4 is a top view of the other embodiment with parts broken away.

In the embodiment according to Figs. 1-3, a stationary bottom plate 1 is supported by a frame, which is not shown in further detail. The mould wheel is constituted by a one-piece casting comprising a boss 2, a rotatable disk 3 and eight open moulds 4, 4^I, 4^{II} . . . 4^{VII} projecting downwards therefrom, and is journaled centrally in the plate 1 and rests upon the same. The wheel is formed with a peripheral bulge 5, so that it may conveniently be rotated like a hand wheel. The die 6, which in the position of the mould wheel

shown in the drawing is situated over the mould 4^I, is carried by a horizontal arm on a rod 7, which is guided vertically in the boss 2. Through a link 8 the rod 7 is connected with a pedal 9 adapted to be trodden down against the action of a spring 11 and having a fixed pivot 10. The expeller 12 is located in an opening in the bottom plate 1 below the mould 4 and is carried by a rod 13 guided vertically in a bracket 14 at the bottom side of the plate 1. A two-armed lever 15 is pivoted in the bracket and connects the expeller 12, 13 with the die rod 7, so that the expeller is moved opposite to the die when the pedal 9 is actuated.

16 is a covering plate, which is carried by a stud 17 fixed to the plate 1 by a screw connection,

and is situated just above the mould 4¹, and which has a circular opening for the die 6 coaxial with the latter. Each of the moulds have a stop 18, which in the expelling position co-operates with a stop 19. The stop 19 is mounted rockably and displaceably on a tangential pivot 20 carried by the plate 1.

An arm 21 integral with the stop 19 bears continuously against the bottom side of the expeller 12, the stop 19 having a bias at the outer side of 12, the stop 19 having a bias at the outer side of the pivot 20 and therefore always tending to rock outwards. Besides, the stop 19 is actuated by a compression spring 22, which is compressed when the stop 18 abuts against the stop 19 during rotation of the mould wheel in counterclockwise direction, as viewed in Fig. 1.

The manner of operation is as follows: One man stands to the left of the press and operates the mechanism, while another man stands to the right and fills the mould with earth. When the man to the left treads the pedal down in the position shown, the die 6 goes down into the mould 4¹ and presses the earth therein, so that a pot is formed. At the same time the expeller 13 is raised and expels a finished pot from the mould 4. The stop 19 then rocks upwardly and leaves the stop 18, whereupon the spring 22 displaces it in the rearward direction in Fig. 1. The man then puts the pot away from the mould 4 and releases the pedal so that the spring 11 draws the die upwards, and the expeller 12 goes down so that the stop 19 is again turned inwards. But because of the displacement of this stop which has taken place, it is now positioned behind the stop 18, so that it no longer bars the counterclockwise rotation of the mould wheel. Then with the bulge 5 the man turns the mould wheel $\frac{1}{8}$ of a revolution, whereby the stop on the mould 4¹ abuts against the stop 19, and the spring 22 is again compressed.

Also in the embodiment according to Fig. 4 the press comprises a central die rod 23 and an expeller plate 24 acting from below, and the mould wheel is cast in one piece with the moulds 26, 26¹, 26^{II} . . . 26^{VII} projecting downwardly therefrom. The actuating mechanism for die rod and expeller may be of the same construction as in the first embodiment. However, in this case the bearing of the mould wheel 25 is at the outside of the boss 27 of the fixed bottom plate, so that the die rod 23 is guided in the boss 27 itself and the latter projects upward through the boss of the mould wheel.

A radial arm 28 is rockably mounted on the boss 27 above the mould wheel 25 and carries the cover plate 29, which in the position shown overlies the mould 26^V in the position preceding the pressing position shown at 26^{VI}. The arm 28 can rock about the boss 27 at an angle which equals the angular displacement of two adjacent moulds and is limited by the abutment of a protuberance 30 on the boss 27 against the extremities of a groove 31 in the boss of the arm 28.

An extension of the arm 28 outside the plate 29 carries a bolt 32 which projects downwardly therefrom. The bolt forms the pivot of a lever 33 formed as a projecting handle having an integral arm 34, which projects forward in the direction of rotation of the wheel 25, and the extremity of which forms a wedge-shaped finger adapted to engage notches 50, 50¹, 50², 50³, 50⁴, 50⁵, 50⁶ and 50⁷ distributed over the periphery of the mould wheel 25 with the same angular distance as the moulds 26—26^{VII}. Behind the lever 33

there is an arm 35 which projects inwards and is adapted to engage a stop 36 on an extension of the arm 28 when the lever 33 is turned clockwise, i. e. opposite to the direction of rotation of the wheel. A compressing spring 37 located in opposite recesses in the arms 28 and 35 tends to turn the lever counterclockwise.

This device operates in the following manner: The operator pulls the lever 33 from the position shown, whereby the mould wheel 25 and the arm 28 with the covering plate 29 are turned until the protuberance 30 stops the movement in the position in which the plates 29 and the mould thereunder are situated centrally under the pressing die 38, then he treads down on the pedal (not shown), whereby the die 38 is lowered and the expeller 24 raised. He then puts the expelled pot aside. He then pushes the lever 33 away from him in the clockwise direction. As 20 a certain pressure from the pot which has just been pressed, is now acting on the bottom side of the plate 29, the latter is withheld by friction, so that the lever turns clockwise, whereby the arm 34 is disengaged from the notch.

The arm 35 then engages the stop 36, and the arm 28 with the plate 29 is entrained backward, whereas the mould wheel remains stationary because of the friction against the base plate, especially at the pot which has just been pressed. During this movement the arm 34 will wipe on the periphery of the wheel 25 because of the spring 37, irrespective whether the friction at the pivot of the lever 33 is greater or smaller than the friction at the bearing of the arm 28, and the arm 34 will enter the next notch in the plate 25 by itself at the same time as the backward rotation is stopped by the protuberance 30.

In order to secure a steady guidance of the lever 33, this lever may be provided with a lug 40 39, which engages the bottom side of the wheel 25, which in this case is of course not made with any peripheral bulge. In order that the operator may adopt a convenient position for actuating the lever 33, a position 26^{VII} is in this case inserted between the pressing position 26^{VI} and the expelling position 26, and in order that the friction may be as small as possible. The opening for the expeller in the bottom plate may also extend past the position 26^{VII}. As no stop is required on the bottom plate outside the expeller opening, the latter may in this case be open at the outside, as indicated with dotted lines at 40.

Apart from the advantage that in this embodiment the movable stop 19, which forms the most delicate part of the construction shown in Figs. 1-3, may be dispensed with, the provision of the rockable covering plate and lever has the advantage that the rotation of the mould wheel 60 becomes considerably easier than in the first embodiment. For, whereas in the embodiment shown in Figs. 1-3 the earth in the pot which has just been pressed, and thereafter exerts a pressure on the covering plate as well as on the bottom plate, which provides a fairly great frictional resistance to the rotation of the wheel, in the embodiment shown in Fig. 4 the energy required for overcoming the friction is distributed without loss of time between two operations, due 70 to the fact that the covering plate is turned back before the mould wheel is rotated. In addition, the friction on the bottom plate is reduced because of the release of the pressure when the covering plate is removed.

Also additional facilitation is obtained due to

the fact that the operator works at a greater radius when the lever is directed outwards from the mould wheel, as shown. Further there is no risk of hurting the hand on the covering plate during rotation.

For filling the moulds a sloping board 41 is shown in Fig. 4, which merges with an integral frame 42 open in top and bottom and is carried by bolts projecting upwards from the bottom plate outside the mould wheel, as indicated at 43 and 44. The frame 42 confines a segment-shaped chamber extending over a plurality of moulds, in the drawing the moulds 26^I . . . 26^{IV}, and projecting from the board 41 in the direction of rotation. Instead of the board 41, a hopper or other feeding member may be used. The earth mass which is spaded or otherwise supplied to the board or the like 41, which slopes towards the mould wheel, is entrained by the rotation of the latter so that it covers the mould wheel over the whole of the chamber confined by the frame. In this chamber it is pressed down into the mould 26^{III} by a pressing plate 45 carried by an arm 46 fixed on the die rod 23. A second pressing plate 47 over the last mould 26^{IV} covered by the frame is carried in a similar manner by an arm 48. The plate 45 may be adapted to be adjusted in the vertical direction and may be secured by means of a set screw 49 for adjusting the desired quantity of earth, whereas the plate 47 may be actuated by a compression spring and supported by a stop, so that it yields resiliently if there is sufficient earth in the mould already, but supplies the required additional quantity if there is not sufficient earth in the mould.

Though it is preferred to use two pre-pressing plates 45 and 47 as shown, it is also possible to use a greater number or, if desired, only one such plate.

I claim:

1. An earth-pot press comprising a stationary bottom plate, a mould wheel rotatable about a vertical axis, a plurality of moulds integral with said wheel and equally spaced about said axis and formed with open bottoms resting on said bottom plate, means for arresting said wheel in predetermined positions, a non-rotatable die-carrying rod extending substantially axially through said wheel, guiding means permitting longitudinal movement of said rod, a downwardly-acting die carried by said rod above said bottom plate and registering with one of said moulds in each of the predetermined positions of the wheel and adapted by downward movement of said rod, to press an earth-pot in the mould registering with the die in each predetermined position of the wheel, an annular covering plate overlying said mould during pressing, means for supporting said covering plate so as to retain the pressed earth within said mould during the return movement of the die, an upwardly-acting expeller registering with a second mould in each predetermined position of the wheel and normally located below said mould wheel, stationary guiding means permitting vertical movements of said expeller, means interconnecting said rod and expeller for simultaneous movements in opposite directions, means for joint actuation of said rod and expeller and retracting means for returning said rod and expeller and retaining them in their normal positions.

2. An earth-pot press comprising a stationary bottom plate, a mould wheel rotatable about a vertical axis, a plurality of moulds integral with

said wheel and equally spaced about said axis and formed with open bottoms resting on said bottom plate, means for arresting said wheel in predetermined positions, a non-rotatable die-carrying

5 rod extending substantially axially through said wheel, guiding means permitting longitudinal movement of said rod, a downwardly-acting die carried by said rod above said bottom plate and registering with one of said moulds in each of the predetermined positions of the wheel, means for maintaining said die in a normal upper position above said wheel, means below said bottom plate for actuating said rod so as to move said rod and die downwards for causing pressing of 10 an earth-pot in the mould registering with the die in each predetermined position of the wheel, an upwardly-acting expeller registering with a second mould in each predetermined position of the wheel and normally located below said mould 15 wheel, stationary guiding means permitting vertical movements of said expeller, and means for causing said expeller to move upwards so as to expel a pressed pot from said second mould, said arresting means comprising a stopping member 20 adapted on operation of the pressing and expelling mechanism to be moved from an operative to an inoperative position and thereafter automatically to return to said operative position.

3. An earth-pot press comprising a stationary

30 bottom plate, a mould wheel rotatable about a vertical axis, a plurality of moulds integral with and projecting downwards from said wheel and equally spaced about said axis and formed with open bottoms resting on said bottom plate, an integral peripheral bulge on said mould wheel permitting the same to be turned like a hand wheel, means for arresting said wheel in predetermined positions, a non-rotatable die-carrying rod extending substantially axially through said

40 wheel, guiding means permitting longitudinal movement of said rod, a downwardly-acting die carried by said rod above said bottom plate and registering with one of said moulds in each of the predetermined positions of the wheel, means for maintaining said die in a normal upper position above said wheel means below said bottom plate for actuating said rod, so as to move said rod and die downwards for causing pressing of an earth-pot in the mould registering with the die in each predetermined position of the wheel, an upwardly-acting expeller registering with a second mould in each predetermined position of the wheel and normally located below said mould wheel, stationary guiding means permitting vertical movements of said expeller and means for causing said expeller to move upwards so as to expel a pressed pot from said second mould.

4. An earth-pot press comprising a stationary bottom plate, a notched mould wheel rotatable about a vertical axis, a plurality of moulds integral with said wheel and equally spaced about said axis and formed with open bottoms resting on said bottom plate, a non-rotatable die-carrying rod extending substantially axially through said wheel, guiding means permitting longitudinal movement of said rod, a downwardly-acting die carried by said rod above said bottom plate and registering with one of said moulds at a time in predetermined positions of the wheel, means for maintaining said die in a normal upper position above said wheel, means below said bottom plate for actuating said rod so as to move said rod and die downwards for causing pressing of an earth-pot in the mould registering with the die in each predetermined position of the wheel,

60 55 70 75

an annular covering plate mounted above the mould wheel, an arm carrying said covering plate and rotatable about the axis of the mould wheel over an angle equal to the angular spacing of adjacent moulds, a handle rockably mounted on said arm and so adapted that when rotated in the direction of rotation of the mould wheel, it engages one of the notches in said wheel so as to entrain the latter in the rotating movement, but when rotated in the opposite direction, disengages the mould wheel and abuts against the said arm so as to rotate the same in the backward direction, an upwardly-acting expeller registering with a second mould in each predetermined position of the wheel and normally located below said mould wheel, stationary guiding means permitting vertical movements of said expeller, and means for causing said expeller to move upwards so as to expel a pressed pot from said second mould.

5. An earth-pot press comprising a stationary bottom plate, a notched mould wheel rotatable about a vertical axis, a plurality of moulds integral with said wheel and equally spaced about said axis and formed with open bottoms resting on said bottom plate, a non-rotatable die-carrying rod extending substantially axially through said wheel, guiding means permitting longitudinal movement of said rod, a downwardly-acting die carried by said rod above said bottom plate and registering with one of said moulds at a time in predetermined positions of the wheel, means for maintaining said die in a normal upper position above said wheel, means below said bottom plate for actuating said rod so as to move said rod and die downwards for causing pressing of an earth-pot in the mould registering with the die in each predetermined position of the wheel, an annular covering plate mounted above the mould wheel, an arm carrying said covering plate and rotatable about the axis of the mould wheel over an angle equal to the angular spacing of adjacent moulds, a handle rockably mounted on said arm and so adapted that when rotated in the direction of rotation of the mould wheel, it engages one of the notches in said wheel so as to entrain the latter in the rotating movement, but when rotated in the opposite direction, disengages the mould wheel and abuts against the said arm so as to rotate the same in the backward direction, a spring acting between said arm and handle and tending to move the handle into engagement with the mould wheel, an upwardly-acting expeller registering with a second mould in each predetermined position of the wheel and normally located below said mould wheel, stationary guiding means permitting vertical movement of said expeller, and means for causing said expeller to move upwards so as to expel a pressed pot from said second mould.

6. An earth-pot press comprising a stationary bottom plate, a notched mould wheel rotatable about a vertical axis, a plurality of moulds integral with said wheel and equally spaced about said axis and formed with open bottoms resting on said bottom plate, a non-rotatable die-carrying rod extending substantially axially through said wheel, guiding means permitting longitudinal movement of said rod, a downwardly-acting die carried by said rod above said bottom plate and registering with one of said moulds at a time in predetermined positions of the wheel, and adapted by downward movement of said rod to press an earth-pot in the mould registering with the die in each predetermined position of

the wheel, an annular covering plate mounted above the mould wheel, an arm carrying said covering plate and rotatable about the axis of the mould wheel over an angle equal to the angular spacing of adjacent moulds, a handle rockably mounted on said arm and so adapted that when rotated in the direction of rotation of the mould wheel, it engages one of the notches in said wheel so as to entrain the latter in the rotating movement, but when rotated in the opposite direction, disengages the mould wheel and abuts against the said arm so as to rotate the same in the backward direction, an upwardly-acting expeller registering with a second mould in each predetermined position of the wheel and normally located below said mould wheel, stationary guiding means permitting vertical movements of said expeller, means interconnecting said rod and expeller for simultaneous movements in opposite directions, means for joint actuation of said rod and expeller and retracting means for returning said rod and expeller and retaining them in their normal positions.

7. An earth-pot press comprising a stationary bottom plate, a notched mould wheel rotatable about a vertical axis, a plurality of moulds integral with said wheel and equally spaced about said axis and formed with open bottoms resting on said bottom plate, a non-rotatable die-carrying rod extending substantially axially through said wheel, guiding means permitting longitudinal movement of said rod, a downwardly-acting die carried by said rod above said bottom plate and registering with one of said moulds at a time in predetermined positions of the wheel, and adapted by downward movement of said rod to press an earth-pot in the mould registering with the die in each predetermined position of the wheel, an annular covering plate mounted above the mould wheel, an arm carrying said covering plate and rotatable about the axis of the mould wheel over an angle equal to the angular spacing of adjacent moulds, a handle rockably mounted on said arm and so adapted that when rotated in the direction of rotation of the mould wheel, it engages one of the notches in said wheel so as to entrain the latter in the rotating movement, but when rotated in the opposite direction, disengages the mould wheel and abuts against the said arm so as to rotate the same in the backward direction, a spring acting between said arm and handle and tending to move the handle into engagement with the mould wheel, an upwardly-acting expeller registering with a second mould in each predetermined position of the wheel and normally located below said mould wheel, stationary guiding means permitting vertical movements of said expeller, means interconnecting said rod and expeller for simultaneous movements in opposite directions, means for joint actuation of said rod and expeller and retracting means for returning said rod and expeller and retaining them in their normal positions.

8. An earth-pot press comprising a stationary bottom plate, a mould wheel rotatable about a vertical axis, a plurality of moulds integral with said wheel and equally spaced about said axis and formed with open bottoms resting on said bottom plate, means for arresting said wheel in predetermined positions, a non-rotatable die-carrying rod extending substantially axially through said wheel, guiding means permitting longitudinal movement of said rod, a downwardly-acting die carried by said rod above said bottom plate and registering with one of said moulds in

each of the predetermined positions of the wheel, means for maintaining said die in a normal upper position above said wheel means below said bottom plate for actuating said rod so as to move said rod and die downwards for causing pressing of an earth-pot in the mould registering with the die in each predetermined position of the wheel, an upwardly-acting expeller registering with a second mould in each predetermined position of the wheel and normally located below said mould wheel, stationary guiding means permitting vertical movements of said expeller, means for causing said expeller to move upwards so as to expel a pressed pot from said second mould, a stationary feeding device, a confining frame merging therewith and extending over a plurality of moulds other than those registering with said die and said expeller, and at least one pressing plate carried by said rod and registering with a mould within the area of said frame in each predetermined position of the wheel.

9. An earth-pot press comprising a stationary bottom plate, a mould wheel rotatable about a vertical axis, a plurality of moulds integral with said wheel and equally spaced about said axis and formed with open bottoms resting on said bottom plate, means for arresting said wheel in predetermined positions, a non-rotatable die-carrying rod extending substantially axially through said wheel, guiding means permitting longitudinal movement of said rod, a downwardly-acting die carried by said rod above said bottom plate and registering with one of said moulds in each of the predetermined positions of the wheel, means for maintaining said die in a normal upper position above said wheel, means below said bottom plate for actuating said rod so as to move said rod and die downwards for causing pressing of an earth-pot in the mould

5
